UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

INTERLOCKING SWITCH DEVICE.

Application filed June 22, 1923. Serial No. 647,093.

To all whom it may concern:

Be it known that I, CLYDE C. FARMER, a citizen of the United States, residing at Pittsburgh, in the county of Allegheny and 5 State of Pennsylvania, have invented new and useful Improvements in Interlocking Switch Devices, of which the following is a specification.

This invention relates to mechanism for 10 interlocking the operation of electric train line switches with operation of the usual cut-out cocks which are employed to open and close communication through fluid pressure train lines when cars are coupled or uncoupled.

The principal object of my invention is to provide means by which, when cars are to be uncoupled, the electric switches must be manually shifted to a position for opening 20 the electric train line circuits, before the cut-out cocks can be manually shifted to the closed position and when cars are to be coupled up, the cut-out cocks must be shifted to the open position, before the switches can be shifted to the cut-in position, in which the 25 electric train line circuits are completed through the couplers.

The purpose of interlocking the operation of the cut-out cocks and electric train line 30 switches is to ensure that there will be no live electric contacts in the electric couplers at the uncoupled ends of the cars when the cut-out cocks are closed. If cars are uncoupled without first closing the cut-out cocks, 35 the discharge of fluid from the open ends of the fluid pressure train line when cars are uncoupled will warn the operator that the cut-out cocks are open and then before the cut-out cocks can be closed the electric 40 switch operating mechanism must be operated to open the electric train line circuits.

My improved interlock mechanism also permits the operation of the electric train line switches to cut off the electric current 45 from a section of the train, without closing the cut-out cocks, so that repairs or inspection may be effected with respect to the electric apparatus in the cut-out section without interfering with the control of the fluid 50 pressure brakes throughout the train.

In the accompanying drawing; Fig. 1 is an elevational view of an interlock mechanism embodying my invention; Fig. 2 a 55 plan view thereof; Fig. 3 a distorted dia-

grammatic view of the interlock mechanism, 55 illustrating how the mechanism operates to interlock the operation of the electric switches and the cut-out cocks; Fig. 4 a side view of the switch operating lever; and Fig. 5 a face view of the switch operating lever. 60

As shown in the drawing, the reference numeral 1 indicates an electric switch portion containing electric switches for opening and closing electric train line circuits. 65 A switch operating lever 2 is provided and when the lever 2 is in the position shown in Fig. 1, the electric switches are in position opening the electric circuits. When the lever 2 is turned counter clock-wise, the switches are operated to close the electric 70 circuits.

The reference numerals 3 and 4 indicate cut-out cocks for opening and closing fluid pressure train pipes at the ends of the cars when cars are coupled or uncoupled. The 75 cock 3 is operable to open and close communication through the corresponding train pipe by means of a lever 5 and the cock 4 by means of a lever 6. An operating rod 7, extending to one side of the car is pivotally 80 connected to lever 5 and an operating rod 8, extending to the opposite side of the car is pivotally connected to lever 6. A link 9 pivotally connects the levers 5 and 6, so that both cocks may be manipulated from either 85 side of the car.

At one end of the switch operating lever 2 is pivotally connected an operating rod 10 which extends to one side of the car, and an operating rod 11, extending to the opposite side of the car is pivotally connected to the opposite end of lever 2. Underneath the lever 2, a slide bar 12 is mounted in suitable guide members provided on the switch portion 1, so as to slide laterally, and one end 90 of said bar is connected by a link 13 to the link 9 and the lever 6, so that whenever the cocks 3 and 4 are operated by the movement of either operating rod 7 and 8, the slide bar 12 must also be shifted. 95

The lever 2 is provided with a boss having an inclined face 14, so disposed as to engage the upper face of slide bar 12 when the lever 2 is in the switch open position, as shown in Fig. 1. The slide bar 12 is provided with 100 a recess 15, so disposed that when the slide bar is in the position to which it is moved when the cut-out cocks are in open position, 105

and the switch lever 2 is in position for closing the electric train line circuits, the inclined face 14 of the lever will occupy a position within the recess 15 and adjacent to the inclined end wall 16 of the recess.

In operation, and referring to Fig. 3 which illustrates the operation somewhat more clearly than Figs. 1 and 2, showing the actual disposition of the parts, the full line position shows the switch lever 2 in its open position and the cut-out cocks 3 and 4 in their closed positions. It will be evident that due to the engagement of the inclined face 14 of lever 2 with the upper face of slide bar 12, the lever 2 cannot be shifted by manipulation of the operating rods 10 and 11. In order to permit the operation of lever 2, either the operating rod 7 or 8 must be shifted so as to turn the cocks 3 and 4 to their open position, as shown in the dotted lines in Fig. 3. In the dotted line position, it will be noted that slide bar 12 has been shifted to the right, so that the recess 15 therein is disposed below the lever 2. In this position, the lever 2 may be turned to its switch closing position, as shown in dotted lines.

In this position of switch lever 2, it will be noted that the inclined face 14 of the boss on lever 2 extends into the recess and is positioned adjacent to the inclined end wall 16 of the recess, so that the inclined face 14 now opposes movement of slide bar 12 to the left and consequently the movement of the cut-out cocks 3 and 4 from their open positions is opposed to their closed positions unless the switch lever 2 is first shifted to its switch open position.

When the parts are in the dotted line positions, shown in Fig. 3, with the cut-out cocks open and the switches closed, it will be noted that the switch lever 2 may be turned to its switch open position while the cut-out cocks are left in their open positions, so that re-pairs or inspection of the electric system of a section of a train may be effected while still maintaining communication through

the cut-out cocks and consequently, the cut-out cocks being left open, the fluid pressure brakes may be operated in the usual manner. 50

Having now described my invention, what I claim as new and desire to secure by Letters Patent, is:

1. The combination with a switch for controlling an electric train line circuit, a casing enclosing said switch, a cock for controlling communication through a fluid pressure train pipe, an interlock member slidably mounted on said casing, a lever for operating said cock, a link pivotally connecting said lever with said member, and a lever for operating said switch and having an inclined face for engaging said member. 55

2. The combination with a switch for controlling an electric train line circuit, a casing enclosing said switch, a cock for controlling communication through a fluid pressure train pipe, an interlock member slidably mounted on said casing, and provided with a recess, a lever for operating said cock, a link pivotally connecting said lever with said member, and a lever for operating said switch and having an inclined face for engaging said member in one position and for engaging in said recess in another position. 65

3. The combination with a switch for controlling an electric train line circuit, a casing enclosing said switch, a cock for controlling communication through a fluid pressure train pipe, an interlock member slidably mounted on said casing and provided with a recess, a lever for operating said cock, a link pivotally connecting said lever with said member, and a lever for operating said switch and having an inclined face for engaging said member in one position whereby said member prevents movement of said switch lever and for also engaging said member in another position, to oppose movement of said member. 75 80 85 90

In testimony whereof I have hereunto set my hand.

CLYDE C. FARMER.
